UNITED STATES PATENT OFFICE.

JACOB GLANTZ, OF PHILADELPHIA, PENNSYLVANIA, ASSIGNOR OF ONE-HALF TO WILLIAM C. KLEIN, OF PHILADELPHIA, PENNSYLVANIA.

ASH-SIFTER.

SPECIFICATION forming part of Letters Patent No. 740,268, dated September 29, 1903.

Application filed April 29, 1902. Serial No. 105,210. (No model.)

To all whom it may concern:

Be it known that I, JACOB GLANTZ, a citizen of the United States, residing in the city and county of Philadelphia, State of Pennsylvania, have invented new and useful Improvements in Ash-Sifters, of which the following is a specification.

My invention consists of an ash-sifter embodying a receptacle, a lid therefor, a sieve, a rod connected with said sieve, and slotted plates which are secured to said receptacle and form bearings for the ends of said rod whereby the sieve may be reciprocated or shaken and the weight of the sieve sustained in the main on said plates.

It also consists of novel means on the receptacle for supporting and reinforcing said plates whereby they are enabled to sustain the severe strain to which they will be subjected during the use of the sieve.

Figure 1 represents a side elevation of an ash-sifter embodying my invention. Fig. 2 represents a vertical section thereof on line *xx*, Fig. 1. Fig. 3 represents a vertical section of a portion on line *yy*, Fig. 1.

Similar letters of reference indicate corresponding parts in the figures.

Referring to the drawings, *A* designates a receptacle. *B* designates a screen at the top of the same, having a peripheral bead *C*, which is freely supported on the top bead *D* of said receptacle, and *E* designates the lid of the device, the same being fitted on the top of the sieve. Connected with said sieve is the horizontally-extending rod or bar *F*, whose end portions pass through the side walls of said sieve and project beyond the same, as at *G H*.

J designates castings or plates, which are secured to the upper portion of the receptacle *A* adjacent to the bead *D*, said plates having therein the horizontally-extending slots *K*, corresponding to similar ones in the receptacle, one end of each slot being in communication with the vertical recess *L* in the bead *D*, corresponding to a similar recess in the receptacle. This forms L-shaped slots by which the ends of the rod *F* may be admitted into the slots *K* of the plates *J* and reciprocated therein, by which provision the ashes may be sifted, the fine particles thereof

then dropping into the receptacle, while the coal and cinders remain in the sieve *B*, it being noticed that while the beads *C D* are in contact and the weight of the sieve is in a measure transmitted by the bead *C* upon the bead *D* the ends of the rod *F*, bearing upon the base-walls of the slots *K*, also receive some of the weight of the sieve and transmits the same to said walls, and thus the plates *J* act as reinforces for the receptacle and additional bearings for the sieve, so that breaking down of the upper portion of the receptacle, where the ends *G H* of the rod *F* have their play, is prevented.

M designates the bottom of a receptacle, on the periphery of which is the downwardly-projecting flange *N*, between which and the base-ring *P* of the device is a recess or groove which receives the lower end of the receptacle *A*, said flange *N* and base being secured together, forming a firm and strong support for the bottom portion of the receptacle.

Q designates strips of resilient material, such as steel, which are vertically disposed on the exterior of the receptacle *A*, one end of each of said strips being firmly connected with the receptacle by rivets or other means, as at *R*, and the other end is freely contained in the sockets *S*, which are secured to the upper portion of the receptacle, by which provision said strips are permitted to have a vertical play in said sockets, it being noticed that the strips are bowed outwardly and form guards around the receptacle, so that when the latter is in use any blows or hard usage imparted to the device are received by the strips, which, as is evident, yield sufficiently as cushions, thus preventing battering or injury to the receptacle. Where the strips *Q* are below the plates *J*, the sockets therefor are located under said plates, thus also bracing the latter.

Various changes may be made in the details of construction without departing from the general spirit of my invention, it being evident that the device is serviceable for sifting articles other than ashes, to which latter, therefore, I do not limit myself.

Having thus described my invention, what I claim as new, and desire to secure by Letters Patent, is—

1. In a sifter, a receptacle provided with a bead at the top of the same, said bead and receptacle being provided with coincident vertical slots, and the receptacle with horizontal 5 slots communicating with said vertical slots, plates secured to said receptacle and having horizontal slots in communication with the horizontal slots in the receptacle and a sieve having a horizontally-arranged rod connected 10 with the same and with its ends projecting outwardly from the side wall of said sieve and adapted to enter said horizontal slots and play therein during the reciprocation of the sieve.
- 15 2. In a sifter, a receptacle having a bead, with slots in the bead and adjacent wall of the receptacle, slotted plates secured to the sides of said receptacle at opposite places, the slots of said plates being in communication with 20 the slots in the wall of the receptacle, combined with a sieve, rods projecting from the side wall of said sieve and adapted to enter the slots of and be seated on said plates, and means on said receptacle for supporting and 25 reinforcing said plates and bead from below.
3. In a sifter, a receptacle having a slotted bead at its upper end and coincident slots in its side wall, slotted plates secured to the | sides of said receptacle at diametrically opposite points with the slots of said plates in 30 communication with the slots in the wall of the receptacle, combined with a sieve having a bead resting upon the bead of the receptacle, a rod passed through said sieve and seated on said plates and passed through the slots 35 of the bead, and means for supporting and reinforcing said plates.
4. In a sifter, a receptacle having peripheral bead with oppositely-disposed vertical recesses and with horizontally-disposed slots 40 beneath said bead, plates secured to said receptacle and having horizontal slots communicating with the slots of the receptacle and with the vertical recesses of the bead and corresponding vertical recesses in the receptacle, a sieve having a bead supported on the bead of the receptacle, a rod projecting at opposite sides beyond the sieve and supported on said plates, and sockets secured to the outer wall of the receptacle beneath and supporting said plates. 45 50

JACOB GLANTZ.
